UNITED STATES PATENT OFFICE

95,900

DESIGN FOR A BOTTLE

John L. Dunnock, Baltimore, Md., assignor to Swindell Brothers, Incorporated, Baltimore, Md.

Application April 17, 1935, Serial No. 56,444

Term of patent 7 years

To all whom it may concern:

Be it known that I, John L. Dunnock, a citizen of the United States, residing at Baltimore city, and State of Maryland, have invented a new, original, and ornamental Design for a Bottle, of which the following is a specification, reference being had to the accompanying drawing.

I claim:—

The ornamental design for a bottle, substantially as shown.

JOHN L. DUNNOCK.
